END LOCK BINDER

Samuel Segal, New York, N. Y., assignor to Wilson-Jones Co., Chicago, Ill., a corporation of Massachusetts

Application January 11, 1946, Serial No. 640,494

6 Claims. (Cl. 129—12)

1

The invention deals with loose leaf binders wherein a pair of spaced covers are hingedly carried by a pair of spaced, relatively rugged and durable sheet metal and flattened tubes. In actual practice the lower tube generally carries spaced posts adapted to removably project through guide openings in the upper tube. To retain the upper tube against disengagement from the spaced posts an end lock is provided. This end lock is controlled by an actuating spindle having a polygonal terminal adapted to be operated by a removable key receivable in an end cap appropriately fastened to the upper bar. However to properly maintain the spindle in alignment with the bearing for the key in the end cap, a stabilizing member was employed. This stabilizing member hitherto was secured or anchored to and within the upper tube by indenting the latter to provide appropriate rib means to interlock with a cooperating groove in the stabilizing member, or the latter was anchored to the upper tube by brazing or welding. In any case special tools and equipment were required. For example a bookbinder who purchases tubes of the type above alluded to for custom jobs generally obtains the flattened tubes in predetermined lengths and subsequently cuts down the tubes to his special requirements. When cut down to such special requirements the bookbinder had appreciable difficulty in the matter of appropriately fastening the stabilizer in the upper tube. In many instances he was without the proper equipment or lacked the skill required to modify the tubes for assembly with the stabilizer. The dominant object of the invention resides in the provision of an end lock in a loose leaf binder wherein the stabilizer may be quickly mounted on the spindle without requiring special skill. Another important object resides in the provision of an end lock of the character alluded to wherein the stabilizer is independent of anchorage to its companion tube by crimping or indenting the latter, and is independent of brazing or welding operations, thus eliminating the use of special equipment. The invention has as a further object to facilitate the work on the part of the bookbinder in the matter of assembling the end lock in the upper tube. A further and important object is realized in the elimination of the many types of end caps or closures for the tubes and makes possible the utilization of a standard end cap having a predetermined located bearing. Other objects are concerned with the reduction in the cost of manufacture of the stabilizer and in the assembly of the latter. Further objects,

2

features and functional and structural advantages of the invention will appear from the following detailed specification considered in the light of the accompanying drawings wherein:

- 5 Fig. 1 illustrates in perspective a fragmentary view of the loose leaf binder.
- Fig. 2 is a horizontal sectional view on the line 2—2 of Fig. 1.
- Figs. 3, 4, 5 and 6 are transverse sectional views 10 on the lines 3—3; 4—4; 5—5; and 6—6 of Fig. 2.
- Fig. 6* is an enlarged fragmentary view of Fig. 3.
- Fig. 7 is an enlarged fragmentary view of Fig. 2.
- 15 Fig. 8 is a longitudinal sectional view on the line 8—8 of Fig. 2.
- Fig. 9 is a fragmentary view substantially similar to Fig. 2 but illustrating another form of stabilizer.
- 20 Fig. 10 is a transverse sectional view on the line 10—10 of Fig. 9.
- Fig. 11 is a view similar to Fig. 9 showing the stabilizer cooperating with the externally threaded cylindrical actuating rod, and
- 25 Fig. 12 is a view similar to Fig. 2 however illustrating the spring clip or stabilizer cooperating with a smooth cylindrical portion of the externally threaded actuating rod.
- The loose leaf binder L is utilized to securely 30 hold a stack of papers S between a pair of covers 10 and 11 hingedly carried by the support or base 12 and the follower 13 each of which is in the form of a flattened tube of relatively durable sheet metal.
- 35 Appropriately secured in any well known manner to the base 12 are the spaced upstanding posts 14 on which are threaded superimposed sheets of the stack S which is clamped against the base 12 by the follower 13.
- 40 Specifically the upper and lower flat walls of the follower tube 13 are provided with aligned openings 15 for removably receiving spaced posts 14. To preclude removal of the follower 13 from the spaced posts 14 an end lock generally denoted 45 16 is utilized and comprises the secondary and primary clamping components 17 and 18 connected to the squared shaped partly exteriorly threaded spindle or actuating rod 19. The secondary clamping component 17 is in the form of an elongated bar of substantially uniform thickness and is provided with a pair of downwardly turned lugs 20 and with a pair of upwardly turned lugs 21. These lugs cooperate with the lower and upper walls of the follower to position component 17 within the follower 13.

Welded to and straddling one end of secondary clamping component are the legs 22 of bearing 23 in which a reduced and cylindrical portion 24 of the square shaped spindle 19 is journaled or rotatably disposed. By reducing the spindle, spaced shoulders 25 are formed and these closely but rotatably straddle bearing 23 to preclude accidental disengagement of the spindle from the secondary clamping component 17.

The primary clamping component 18 may be said to be a carriage or shoe having the spaced internally threaded bearings 26 engaging the rotatable and threaded spindle 19. Consequently if the latter be rotated relative to the bearing 23 of the secondary clamping component 17, the primary clamping component 18 is displaced along spindle or actuating rod 19. Component 18 includes an upturned arcuate lip 27 and the latter together with the curved bearings 26 are slidably guided by the arcuate sides of the follower 13.

Mounted on the smooth part 28 of the square shaped spindle 19 are the spaced arms 29 of the U-shaped spring clip or stabilizer 30 having its curved or closed end 31 disposed within an adjacent curved side of the follower 13. The terminals 32 of the spaced and resilient arms 29 of the spring clip 30 are biased, that is diverge away from each other and the circular walls of openings 33 in each of the biased terminals 30 cooperate with the apices or corners 34 of the smooth portion 28 of the spindle 19 to firmly wedge against these corners or apices. Normally the arms 29 are widely diverged due to their own resiliency. In mounting the arms 29 on the polygonal or squared shaped end 28 of the spindle 19, the diverged terminals 32 are pressed towards one another to dispose their circular openings 33 in alignment to receive end 28. Thereafter while the terminals are still pressed towards one another, the arms 29 may be slid along the end 28 to a desired position after which finger pressure is removed from the arms 29. The latter now automatically spring apart to frictionally and wedgeably engage the apices or corner portions 34 whereby the spring stabilizer 30 is maintained in a set and clamped relation within the tube or follower 13. Such action is also enhanced in that spindle 19 is of a metal softer than the metal of the spring clip or stabilizer 30. Thus if the stabilizer is mounted on the spindle it is prevented from accidental dislodgement. However, if desired, the stabilizer 29 may be shifted or adjusted along the rod. This is accomplished by finger pressing the biased terminals 32 toward each other. This releases their grip or clamping action on the spindle. Hence the stabilizer may be shifted along the spindle to a desired location after which finger pressure is removed from the biased terminals and the arms 29 again release or spring outwardly automatically thus causing the biased terminals 32 again to frictionally bind or wedge against the apices or corners 34. Prior to mounting the end lock 16 in the follower 13 the spring clip or stabilizer 30 may be removed from the spindle. This is accomplished by first manually releasing the grip of terminals 32 and thereafter manually shifting the stabilizer to be free of the smooth end 28.

With the stabilizer 30 receiving end 28 of the spindle and properly disposed in the tube 13, the outer terminal 35 of the spindle 19 is held in alignment with the opening or bearing 36 (Fig. 2) in an adjacent end cap or closure 37 fastened

to the follower 13. In fact both ends of the follower 13 and the base or tube 12 are each provided with a cap or closure as 37 but only the cap adjacent outer free terminal 35 of the spindle includes a bearing 36 for removably receiving key or socket K adapted to receive and actuate terminal 35 of the spindle 19 to rotate the latter.

The external contour of the spaced arms 29 of the spring clip or stabilizer 30 conforms substantially to the cross sectional shape of the bore of the follower 13, thus preventing accidental vertical and transverse displacement of the spring clip relative to the follower.

As shown in Fig. 2, the follower 13 may be considered as locked or frictionally clamped against the spaced posts 14 in that the wall of notch 38 of the primary clamping component 18 frictionally bears against and is interlocked with one of the posts 14 while the stabilizer end 39 of the secondary clamping component 17 is abutting and bearing against the other post 14. Thus the follower 13 is prevented from accidental removal from the posts 14. However to allow such removal, the primary and secondary complements 18 and 17 are unclamped from these posts. This is accomplished by placing the key K in the bearing 36 and onto the terminal 35 of the spindle 19. Now by rotating the key in one direction, the spindle or actuating rod 14 is rotated, thus causing the rectilinear end 39 of the secondary clamping component 17 to retract from its adjacent post 14. Thus the overall linear distance between the end 39 and the notched end 38 is decreased, hence relieving the clamping pressure of these ends on the spaced posts 14. Or in other words, the primary and secondary components are unlocked from the posts 14. Consequently the follower 13 may be slidably removed from the posts 14. Hence access is had to the stack S to alter or replace the latter.

Subsequently the follower is again mounted on the spaced posts 14 and dropped against the stack S. Thereafter the follower is locked to the posts by rotating spindle 19 with the aid of the key K. By such action, the primary component 18 and more particularly the wall of notch 38 first reaches and abuts its adjacent post 14. Thereafter on further rotation of the spindle in the same direction, the secondary component 17 draws away from the primary component 18 and ultimately its rectilinear end 39 reaches and abuts its adjacent post 14. On further rotation of the spindle in the same direction, the outer ends 38 and 39 of the primary and secondary components 18 and 17 firmly bind and clamp against the posts, thus desirably disengageably locking the follower 13 to the posts.

On rotating the key in a counter direction, the primary and secondary components 18 and 17 are disengaged from the spaced posts 14. However, a pin 40 (Fig. 8) fastened to the upper and lower walls of the follower tube 13 and interposed between the primary and secondary components serves as stop means to limit the displacement of the end lock 16 in the follower 13.

In the embodiment according to Figs. 9 and 10, the stabilizer is in the form of a plate or bar 50 having an external contour substantially conforming to the internal cross sectional contour of the hollow follower 13 although slidably guided therein. This plate includes the internally threaded opening 51 interlocking with the teeth 34 on the corners of the square shaped actuating spindle or rod 19. The stabilizing plate 50 always holds the spindle 19 in alignment

ment with the bearing or opening 36. The square shaped terminal 35 removably fits into the key K which is projected through the bearing 36. Hence the spindle may be adjusted to clamp or unclamp the primary and secondary components 18 and 17 against and from the spaced posts 14. In Fig. 11 the actuating spindle 19 is cylindrical and threadably engages with the internally threaded stabilizing bar or plate 50. In other aspects the embodiment according to Fig. 11 is substantially along the lines of the form shown in Fig. 9. In Fig. 12 the actuating spindle 19 is of the type shown in Fig. 11 except it is provided with an externally smooth cylindrical portion 52 frictionally and removably engaged by the biased and perforated ends or terminals 32 of the spaced arms 29 of the spring clip or stabilizer 30 of the type illustrated in Figs. 2 and 6^a. In all of the embodiments disclosed the stabilizer maintains the square shaped terminal 35 of the spindle in alinement with the bearing 35 of a fixed closure cap 37.

In all of the forms disclosed the stabilizing means 30 or 50 may be said to be displaceable along the rotatable spindle and slidably guided by the interior walls of the follower or upper flattened tube 13 and of course the stabilizer may be disengageably removed from the spindles. In Figs. 2 and 12 this may be carried out by moving the biased or diverged ends 32 of the resilient arms 29 towards each other, thus removing their wedging action and consequently the U-shaped spring clip or stabilizer may be disengaged or removed from the spindle. In Figs. 9 and 11 by rotating spindle 19 enough in one direction the stabilizing bar 50 may be detached from the spindle. In actual practice however, the bar 50 is positioned appreciably away from the squared terminal 35 to prevent accidental dislodgement from the spindle 19 as the latter is rotated to clamp or unclamp components 17 and 18 from the binding posts 14.

Various changes may be made in details of construction and arrangement of parts without departing from the spirit of the invention or sacrificing any of the advantages thereof inherent therein.

I claim:

1. In a tubular follower for a loose leaf binder wherein spaced parts are removably clamped by slidably guided components within said follower, an externally threaded spindle within and disposed longitudinally of said follower and operatively interconnecting said components and having a non-circular terminal, a closure cap carried by said follower and having a bearing, and a stabilizer within said follower and having spaced resilient arms having biased and perforated ends for receiving said spindle for sustaining said terminal in alinement with said bearing.

2. In a tubular follower for a loose leaf binder wherein spaced posts are removably clamped by slidably guided components within said follower, an externally threaded spindle within and disposed longitudinally of said follower and operatively interconnecting said components and having a non-circular terminal, a closure cap carried by said follower and having a bearing, and a substantially U-shaped spring clip within said follower and having spaced resilient perforated arms surrounding and engaging at least a part

of said spindle for sustaining said terminal in alinement with said bearing.

3. In a tubular follower for a loose leaf binder wherein spaced posts are removably clamped by slidably guided components within said follower, an externally threaded spindle within and disposed longitudinally of said follower and operatively interconnecting said components and having a non-circular terminal, a closure cap carried by said follower and having a bearing, said spindle having a polygonal portion defining apices, and a spring clip within said follower and having spaced arms including biased perforated ends surrounding said spindle and frictionally engaging said apices for sustaining said terminal in alinement with said bearing.

4. In a tubular follower for a loose leaf binder wherein spaced posts are removably clamped by slidably guided components within said follower, an externally threaded spindle within and disposed longitudinally of said follower and operatively interconnecting said components and having a non-circular terminal, a closure cap carried by said follower and having a bearing, said spindle having an externally smooth portion, and a spring clip within said follower and having spaced arms including biased perforated ends surrounding said spindle and frictionally engaging said smooth portion for sustaining said terminal in alinement with said bearing.

5. In a tubular follower for a loose leaf binder wherein spaced posts are removably clamped by slidably guided components within said follower, an externally threaded spindle within and disposed longitudinally of said follower and operatively interconnecting said components and having a non-circular terminal, a closure cap carried by said follower and having a bearing, said spindle having a cross sectionally squared portion defining apices, and a stabilizer within said follower and having spaced resilient arms having diverging perforated ends surrounding said spindle and frictionally engaging said apices for sustaining said terminal in alinement with said bearing.

6. In a tubular follower for a loose leaf binder wherein spaced posts are removably clamped by slidably guided components within said follower, an externally threaded spindle within and disposed longitudinally of said follower and operatively interconnecting said components and having a non-circular terminal, a closure cap carried by said follower and having a bearing, said spindle having an externally relatively smooth cylindrical portion, and a spring clip within said follower and having spaced arms including diverging perforated ends surrounding said spindle and frictionally engaging said portion for sustaining said terminal in alinement with said bearing.

SAMUEL SEGAL.
